UNITED STATES PATENT OFFICE.

ELBERT H. CARROLL, OF WORCESTER, MASSACHUSETTS, ASSIGNOR TO MORGAN CONSTRUCTION COMPANY, OF WORCESTER, MASSACHUSETTS, A CORPORATION OF MASSACHUSETTS.

WIRE-DRAWING BLOCK.

1,173,707.

Specification of Letters Patent. Patented Feb. 29, 1916.

Application filed February 28, 1913. Serial No. 751,246.

To all whom it may concern:

Be it known that I, ELBERT H. CARROLL, a citizen of the United States, residing at Worcester, in the county of Worcester and 5 Commonwealth of Massachusetts, have invented a new and useful Improvement in Wire-Drawing Blocks, of which the following is a specification accompanied by a drawing, forming a part of the same.

10 The object of my present invention is to provide a support in the rigid framework by which the operative parts of the wire drawing block may be supported against gravity, thereby relieving the vertical driving 15 spindle from the weight of the block. This object I accomplish by means of the construction and arrangement of parts as hereinafter described, the novel features being pointed out in the annexed claims.

20 Referring to the accompanying drawing which shows a central, vertical, sectional view of a wire drawing block and supporting table or framework therefor, the vertical driving shaft being shown in full, 1, 1, 25 denotes the table or framework, provided with a journal bearing 2 in which is journaled an upright shaft 3, carrying at its lower end a bevel gear 4 which is engaged by a similar bevel gear on a driving shaft, 30 not shown, in the usual manner in machines of this class.

Mounted upon the vertical shaft 3 is a wire drawing block comprising a cylindrical shell 5 about which the wire is wound 35 and drawn through a reducing die. Between the vertical shaft 3 and the cylindrical shell 5 I interpose a clutching mechanism, which in the present instance consists of a cylindrical drum 6 surrounded by a 40 spiral spring 7. The drum 6 is carried upon the squared section 8 of the driving shaft 3, by which the rotative movement of the shaft 3 is imparted to the drum 6, at the same time permitting a slight longitudinal 45 movement of the shaft 3 within the drum. The lower end of the drum rests upon an antifriction ring 9 which lies in the bottom of a cup shaped oil receptacle 10 to which the lower end of the spiral spring 7 50 is attached.

When the spiral spring 7 is wound tightly about the periphery of the drum 6 by means of an operative mechanism, not shown, but in common use in wire drawing blocks of 55 this class, the spring and its attached cup

shaped oil receptacle 10 are caused to rotate with the drum 6. The drum 6 becomes the driving member of a clutching mechanism, and the spiral spring and its attached oil receptacle 10 the driven member of a clutching mechanism which is capable of being thrown into and out of engagement at will by the operator. The cylindrical shell 5 upon which the wire is wound in the process of wire drawing, is provided at its lower end with an internal flange 11 supported upon and carried by the cup shaped oil receptacle 10. The cup shaped oil receptacle 10 therefore supports the weight of both the drum 6 and cylindrical shell 5. As the coil of wire accumulates upon the cylindrical shell 5 the load supported by the oil receptacle 10 is materially increased.

60 In order to provide a suitable support for the superimposed load upon the oil receptacle which shall relieve the shaft 3 of downward pressure, I provide an annular oil receptacle with an interior flange 12 which rests upon a flange 13 formed upon the upper end of the antifriction lining 14 of the journal bearing 2. The flange 13 overlaps and is supported by the journal bearing 2 which forms an integral part of the framework 1. By causing the flange 65 12 to rest upon the lining 14 I secure an antifriction bearing similar to that between the lower end of the drum 6 and the antifriction ring 9. The entire weight of the operative mechanism driven by the squared section 8 of the vertical shaft 3 is thereby supported upon the rigid table or framework 1, relieving the shaft 3 of its weight. The lower end of the shaft 3 is supported 70 in a step bearing, a portion of which is shown at 15. The bevel gear 4 has a spline connection with the shaft 3 with its hub inclosed within the step bearing 15 and the journal bearing 2 in the frame 1. Between the bevel gear 4 and the journal bearing 2 75 and step bearing 15 I interpose antifriction rings 16 and 17 which are surrounded by the annular oil recesses 18 and 19.

80 I have not deemed it necessary to illustrate or to describe in detail the clutching mechanism and the means for throwing it into and out of engagement as it forms no part of my present invention which relates solely to the construction above described, 85 by which the weight of the entire wire 90 95 100 105 110

drawing block and its inclosed clutching mechanism is supported upon the central journal bearing of the shaft 3 which is integral with the table 1 or framework of 5 the machine.

I claim,

1. The combination of a table or framework having a journal bearing for a vertical shaft, a shaft journaled in said bearing, a 10 wire drawing block inclosing the upper end of said shaft, slideable longitudinally of and connected to rotate with said shaft, and means for supporting the weight of said block upon said journal bearing.
- 15 2. The combination of a vertical shaft, a wire drawing block connected to said shaft so as to rotate therewith and capable of a vertical movement independently of said shaft, a fixed framework beneath said block, 20 and means for supporting the weight of said block in said fixed framework.
- 25 3. The combination of a vertical shaft, a wire drawing block, a clutching mechanism between said block and said shaft having a slideable mounting on said shaft and rotatably connected thereto, and means for supporting the weight of said block and said clutching mechanism independently of said shaft.
- 30 4. The combination of a shaft, a drum

having a rotative connection with said shaft but capable of a longitudinal movement thereon, a cup shaped oil reservoir surrounding said drum, a clutching mechanism between said oil reservoir and said drum, a 35 wire drawing block carried by said oil reservoir, and means for supporting said oil reservoir independently of said shaft.

5. The combination of a shaft, a drum slideable longitudinally of said shaft but connected to rotate therewith, said drum being supported independently of said shaft, a wire drawing block driven by said drum, and means for supporting said drum and wire drawing block, whereby the shaft is 40 relieved of the weight of said drum and block.

6. The combination of a shaft, a bearing for said shaft, a drum slideable longitudinally of said shaft but connected to rotate 45 therewith, a wire drawing block driven by said drum, and a support for said drum and block, said support being carried by said bearing, whereby said shaft is relieved of the weight of said drum and block. 50

Dated this 24th day of February 1913.
ELBERT H. CARROLL.
